UNITED STATES PATENT OFFICE.

JOSEPH H. MOSER, OF DUNLAP, KANSAS.

HAY-SHOCKER.

1,316,630.

Specification of Letters Patent. Patented Sept. 23, 1919.

Application filed March 4, 1918. Serial No. 220,338.

To all whom it may concern:

Be it known that I, JOSEPH H. MOSER, a citizen of the United States, residing at Dunlap, in the county of Morris and State 5 of Kansas, have invented certain new and useful Improvements in Hay-Shockers, of which the following is a specification.

This invention relates to binders, and more especially it is a shocker, wherein the 10 shock is made by hand; and the object of the same is to produce a two-man machine in which one attends to the raking up and delivering of the hay to the table, and the other attends to the formation of the shock 15 on the table and the dumping of the same when formed.

The invention comprises certain details of structure herein more fully set forth and claimed, and reference is made to the drawings, wherein:

Figure 1 is a plan view of this machine complete,

Fig. 2 is a rear elevation with parts in section,

Fig. 3 is a longitudinal section through the table.

The machine includes a running gear propelled by power attached to the tongue 1 which is shown in Fig. 1 as extending back 30 under the table to the main axle 2 and braced by hounds 3, and which tongue is shown as having a whiffletree although of course the latter would not be used if the traction power were a machine. The axle carries at 35 its outer end an idle wheel 5 and at its inner end a main drive wheel 6 which latter assists in supporting both the table and the platform. The table is a rectangular structure whose body is mostly made up of a movable bottom 7 consisting of an endless belt moving over rollers as best seen in Fig. 3. Around this movable bottom is a fixed platform 8 except at the rear end, and around the platform an upstanding wind shield 9. 40 Across the rear end is hinged a gate 10 which when closed to upright position is latched as at 11 and the latch may be tripped by drawing on a chain or cord 12, or it might be tripped by the operator who stands on the 45 table. Another latch 13 at the front edge of the table engages normally with a staple 14 in the tongue 1, and when this latch is moved by means of a handle 15 the front edge of the table is free and the entire table 50 may dump. Across the back of the table is a shaft 16 carrying two spur wheels 17

which engage the earth when the table dumps, and this shaft also has gearing 18 connecting it with the rear roller 19 of the endless belt constituting the movable bottom. 60 Therefore when the table dumps and the spur wheels revolve forwardly, the gearing causes the endless belt to move in a direction which will deliver off the rear end of the table anything that rests thereon. The operator on the table must of course release the forward latch before he dumps the table by passing a little to the rear of its center, and he must either open the gate 10 or see that the other operator does so. After the load has been dumped, he can restore the parts to the position shown in Fig. 3 by stepping forward 70 of the axle on the side platform 8 and latching the parts as herein shown, and then he can step to the rear and close and latch the 75 gate.

The inner end of the main frame 20 of the platform is supported in any appropriate manner by bearings on the main axle adjacent the driving wheel 6, and its outer end is preferably supported by a caster wheel 21. This end of the platform may be drawn forward by an additional horse hitched to the whiffletree 22 as indicated in Fig. 1. The gathering or raking teeth 23 80 are pivotally mounted over the front bar of the frame 20 and their forward ends sustained by a bar 24 extending through all of the teeth, which bar is raised or lowered by lever mechanism 25 standing at the right 85 of the driver's seat 26 as seen in Figs. 1 and 2. The rear ends of the teeth 23 extend back to different distances over an endless apron or carrier 27 which passes around suitable rollers within the frame 20 and is intended 90 to move to the left just forward of the driver, and the rear ends of the teeth are graduated in length for the purpose of delivering the hay onto this carrier in such manner that the latter will pick it up most 95 effectively and carry it inward to the shocker. The wind guard along the rear frame bar 20 is not shown, but it may be placed there and may be carried around the outer end of this frame if desired so that 100 a strong blast of wind will not interfere with the successful operation of the machine. To move the carrier 27, power is taken from a sprocket wheel located preferably on the outer end of the hub of the main drive wheel 105 6, and communicated to another sprocket on the main shaft 28, whence it is conveyed by 110

gearing 29 to the roller at the inner end of the carrier 27 in a manner which will be clear without going further into details. A hand lever 30 at the left of the driver's seat 5 may control a clutch within the main shaft 28 or may slide one of the gears thereon so that he can stop and start the movements of the carrier 27 and the elevator next to be described.

10 The main frame 20 carries an elevator frame 31 inclining upward over the main drive wheel 6, as best seen in Fig. 2, and within the elevator frame is mounted an endless belt elevator 32 whose lower roller 15 is connected by the gearing 29 with the main shaft 28, and an idle belt 33 whose lower stretch stands just above the upper stretch of said elevator, so that the hay between these stretches is carried upward as indicated by the arrows in Fig. 2. The side boards of the frame 31 and the idle belt 33 prevent a strong wind from blowing the hay off the elevator. The upper end of the latter delivers into a shocking frame or ring 20 35 which is sustained above the table by means of converging uprights 36, and this ring may be used as a handle by the operator on the table, to steady himself while at work. It may also be used by him to assist in forming the shock. But it should be large enough to permit the table to be dumped as above described without interfering with the elevator frame.

30 When this machine is drawn forward by a team of horses or by three horses or other draft power, the teeth pick up the hay and may be adjusted by the driver by manipulat-

ing lever 25. They deliver the hay onto the carrier 27 which conveys it inward to the elevator, and the latter carries it upward 40 and drops it through the ring onto the table. Here the other operator forms it into shocks or bundles, and these from time to time are dumped off the rear end of the table in a manner first above set forth. I consider this 45 an extremely simple machine for performing the work it has to do, and as simplicity avoids expense, it can be put within the reach of the average farmer.

What is claimed as new is:—

50 In a hay shocker, the combination of a main support having a table pivoted intermediate the ends thereof, means for conveying hay and depositing the same upon said table, said table including a longitudinally moving endless conveyer in the bottom thereof, a substantially U-shaped platform carried by said table and surrounding the forward end of each side of the conveyer, whereby the operator may walk along the 55 platform for tilting the table, as described, means for driving the endless conveyer, a shocking ring carried upon the table and supported thereon by downwardly diverging uprights which are connected to the ring and to the table, said uprights therefor allowing the operator to hold thereto as the 60 table is being swung upon its support.

65 In testimony whereof I affix my signature in presence of two witnesses.

JOSEPH H. MOSER.
